UNITED STATES PATENT OFFICE

2,580,366

PUNCH CONSTRUCTION

Jacob A. Smith, Chicago, Ill., assignor of one-half
to Claude A. Benjamin, Chicago, Ill.

Application April 28, 1950, Serial No. 158,807

2 Claims. (Cl. 164—124)

1

This invention relates to punch constructions and, more particularly, to a construction for punching accurately located non-circular holes in sheet material.

In punching operations it is desirable to have the punch so constructed that breakage is minimized, but so that the punches can be easily removed and replaced for sharpening or for replacing broken punches. It is also essential that the punch be accurately mounted so that the hole will be properly positioned, and in the case of non-circular punches the angular position is also critical. It is one of the objects of the present invention to provide a punch construction which accomplishes these several objectives.

Another object is to provide a punch construction in which the punch is located by a relatively short locating bore at the outer end of a mounting quill. Preferably the locating bore is non-circular in section and receives a correspondingly shaped locating section on the punch, the remainder of the bore and punch being of cylindrical sections.

Still another object is to provide a punch construction in which the quill is formed with three aligned bores, the outermost of which is the locating bore and receives a relatively short punch, having a cylindrical body fitting into the intermediate bore, a relatively short cylindrical head in the largest bore, and a locating section in the locating bore, and in which the punch is held in the quill by a back-up pin in the largest bore.

The above and other objects and advantages of the invention will be more readily apparent from the following description when read in connection with the accompanying drawing, in which:

Figure 1 is a side elevation with parts in section showing a punch construction embodying the invention;

Figure 2 is an assembled view of the punch construction with the quill in section; and

Figure 3 is a disassembled view of the punch construction.

The punch as shown in Figure 1 may be used with a conventional press having a punch pad 10 movable toward and away from a base or die supporting plate 11. One or more punches may be held on the pad 10 by a holding plate 12 detachably secured to the pad and formed with cylindrical openings 13 to receive quill bodies. The openings 13 terminate at the upper end of the holding plate in enlarged sockets 14, which are preferably non-circular in section, to receive

2

similarly shaped heads on the quill. In the construction shown, the quill is provided with a head 15 which is generally cylindrical but which is formed with a flat spot 16 to fit into a similarly shaped socket in the holding plate, thereby to fix the angular position of the quill accurately and easily.

The punch construction of the invention includes a quill having a head as described above and a body 17 cylindrical on its outer surface. The quill is provided with three aligned bores, including a bore 18 of maximum diameter extending from the upper or head end of the quill throughout the major portion of the quill length. The bore 18 connects to an intermediate bore 19 which is cylindrical and which is connected to the bore 18 by an internal shoulder 21. At the outer end of the quill is a short locating bore 22, which is preferably non-circular in section. In the construction shown, the bore 22 is square, although this exact shape is not critical. In forming a quill as shown, the cylindrical bores 18 and 19 may be drilled in any desired manner to be co-axial, and since these bores extend through substantially the full length of the quill the locating bore 22 can be made very short. The bore 22 can be broached or otherwise formed to a non-circular section, but since it is extremely short this operation can be performed inexpensively and with the necessary degree of accuracy.

The quill is adapted to receive a relatively short punch, having a main cylindrical body 23 of a diameter and length to fit in the intermediate bore 19. Preferably the body 23 is slightly shorter than the bore 19 so that a slight clearance will be left between the body and the punch locating section. At its upper end the body is formed with a cylindrical head 24 of a size to fit into the bore 18 and which is connected to the punch body by an annular shoulder to fit against the internal shoulder 21 in the quill. At its lower end the punch body is formed with a reduced locating section 25 of the same shape as the locating bore 22 to be received in the locating bore. Beyond the locating section 25 is a reduced punch tip 26 to project beyond the end of the quill when the parts are assembled. The punch is held against displacement in the quill by a cylindrical back-up pin 27 which fits in the bore 18 and rests against the punch pad when the punch is assembled in a press.

With this construction, when the punch is used, the impact force produced in the punch itself when it pierces the metal is taken by the

enlarged head 24 of the punch. Since the punch is relatively short this impact force is held down to a relatively low value so that punch breakage beneath the head will be minimized. Furthermore, formation of the punch with several different diameters increasing to a maximum at the head tends to distribute the stresses more evenly throughout the punch body, further to assist in reducing breakage. The back-up pin 18, being free to shift in the quill, is subjected to no breaking forces.

Also, with the present construction, it will be seen that the locating section 25 of the punch, in cooperation with the locating bore 22 of the quill, performs the major part of the function of locating the punch accurately. Since these parts are relatively short, they can be formed with an extremely high degree of accuracy without making the cost of the assembly excessive. When the locating section and the locating bore are non-circular as shown, they additionally, in conjunction with the flat spot 16 on the quill head, provide an accurate angular positioning of the punch tip. This is extremely important in cases where a non-circular punch tip 26 is employed.

In the event a punch must be removed for sharpening or replacement the holding plate 12 can be detached from the punch pad and the quill can easily be removed therefrom. With the quill removed the back-up pin and punch can be taken out of the quill and a new punch or the same punch resharpened and easily reinserted in the quill. It will be observed that it is impossible in this operation to reassemble the parts in an incorrect position and that the entire operation can be performed very simply and quickly. Furthermore, since the punch is a relatively small unit, it is inexpensive and can be replaced much more cheaply than an integral part construction.

While one embodiment of the invention has been shown and described in detail, it will be understood that this is illustrative only and is not to be taken as a definition of the scope of the invention, reference being had for this purpose to the appended claims.

What is claimed is:

1. A punch construction comprising a tubular quill having three aligned bores of progressively decreasing area joined by internal shoulders, the smallest of said bores being at the outer end of the quill, and being non-circular in section, a punch having a relatively short head fitting in the largest bore, a body fitting in the intermediate bore, a locating section of the same cross section as and fitting into the smallest bore, and a tip of non-circular section projecting from the quill, the head being joined to the body by an external shoulder fitting against one of the internal shoulders, and a back up pin fitting in the largest bore and seating against the head.

2. The construction of claim 1 in which the quill includes a generally cylindrical head at the end opposite the smallest bore with a locating portion thereon deviating from the general cylindrical outline of the head.
